UNITED STATES PATENT OFFICE

ARNOLD J. TANNER, OF NORTH HAVEN, CONNECTICUT, ASSIGNOR TO EINSON-FREEMAN CO., INC., OF LONG ISLAND CITY, NEW YORK, A CORPORATION OF NEW YORK

EASEL OR SUPPORTING DEVICE FOR DISPLAY BOXES, SHOW CARDS, AND THE LIKE

Application filed June 29, 1929. Serial No. 374,633.

The present invention has relation to boxes or devices for displaying or advertising merchandise and the invention consists of a novel construction of an easel or supporting means designed especially for display boxes which may however be applied with advantage to display or show cards. The invention is particularly applicable to folding display boxes of a certain type having two containing sections so hinged together as to fold into an open position wherein the sections are placed one behind and above the other. In this position, it is necessary to support the rear or elevated section, and for this purpose, numerous forms of easels have been proposed.

It is the object of the present invention to provide a more efficient supporting means and one that is simple in construction so that it may readily be set up in position for operation by an inexperienced person. Furthermore, another object is to provide an easel which will facilitate the manufacture and assembly of the same in connection with the blank of which the box for example is composed. According to the present invention, the easel or support is a separate member or piece and is readily secured to the box blank and retained in place by self-retentive means. Several embodiments of the invention will be described hereinafter with reference to the accompanying drawings wherein—

Figure 1 is a perspective view showing the improvement as applied to a so-called double tier display box which is shown in its open or display position;

Figure 2 is a perspective view showing the said box in its closed or shipping position;

Figure 3 is a perspective view showing the invention as applied to a show card;

Figure 4 is a longitudinal sectional view of the device as applied to a show card;

Figure 5 is a sectional view showing another position of the improved easel;

Figure 6 is a cross section showing the easel in one open or operative position;

Figure 7 illustrates a modification;

Figure 8 is a plan view of a blank which forms a body to be supported, and

Figure 9 is a plan view showing the easel blank.

Referring to said drawings, particularly to Figures 1 and 2 wherein the invention is shown as applied to a double tier box composed of two containing sections 1 and 2 which are hinged together at the line 3. These sections are so arranged that they will fold together end to end to form a convenient shipping package as shown in Figure 2. When it is desired to set the box up for display purposes, the sections are unfolded so that one section will swing on the scored line 3 which is above the center as shown so that the bottom of the rear section lies in a higher plane than the bottom of the front section.

The improved easel provides a supporting base for the sections of the box when set up for display and the easel is composed of a single separate strip 4 which is scored on the lines 5 so as to fold into the operative or open position as shown in Figure 1. In the inoperative position, said easel folds flat against the back wall of the box as shown in Figure 2. The retention of the easel is effected by means of the extending side sections or wings 6 being engaged so as to slide in slots 7 formed in the back wall of the box. Said wings 6 preferably have the recess 8 to receive and hold the bottom of the rear box section 1 against the other or front section 2, which latter section carries the easel 4. It will be noted the outward sliding movement of the easel is limited by the stops 9 so that when the easel is opened it is prevented from being pulled out entirely.

Referring to Figures 3, 4, 5 and 6 of the drawings, herein the invention is shown as applied to a showcard and with this example, the easel is constructed and arranged substantially the same as in the example previously described. In the position shown in Figures 3 and 4, the easel is in its outward or operative position and is so arranged that merchandise, for example a carton, may be placed upon said easel and be supported in a display position relatively to the card which forms a background therefor. The side pieces 6 have the recesses 7 which receive the

said carton but which recesses may obviously be dispensed with in some cases. The side pieces 6 slide freely in the slots 7' therefore the card may be placed in several angular positions as shown in Figures 4 and 5 so as to get the desired angle for display.

It will be understood that conditions are apt to be variable and generally the conditions are determined by the relative width 10 and height of the body to which the easel is connected. In the example shown, the easel when in its flat or unfolded position is substantially the same length as the width of the body. As shown in Figure 6, when the easel is in its open or folded operative position, the easel is wider at its base than at its outer end so as to form an angular shape which offers the maximum of rigidity obtainable with the material employed. It will be understood in this form the easel will not easily collapse. In Figure 7, the easel is shown as being of substantially rectangular shape so that it will fold to either side of the body or if central scored lines are provided 20 in the side pieces 6 at the point 9, the easel will collapse on itself as shown in broken lines. An easel of this kind is preferably employed when the body carrying the easel is comparatively narrow.

The easel hereinbefore described is applied to the blank in a very simple manner by first inserting the outer end or stop 8 of one side piece 6 into its respective slot and then by turning the same slightly, the rounded end 35 10 will permit the full insertion of side piece 6. The other side piece 6 is then inserted in a similar manner and the easel before folding, lies flat against the body as shown in Figure 2. To open the easel, the same is simply pulled outwardly and if properly constructed, it will practically spring into its outward or operative position and be held in this position by self-retentive means.

Various modifications may be made in carrying out the details of the invention hereinbefore described but it is to be understood that any modification coming fairly within the terms of the appended claims shall 40 be covered thereby.

I claim:

1. A foldable adjustable easel as described composed of a single piece creased to form a central section and side sections, a body supported by said easel, said body having slots 55 to receive said side sections so as to permit sliding movement thereof whereby said easel may be adjusted into several operative positions or placed in its inoperative position 60 wherein said easel lies flat against said body and means on the end of said side sections to limit the outward movement of the easel.

2. A foldable adjustable easel as described composed of a single piece creased to form a central section and side sections, a body sup-

ported by said easel and said body having slots to receive said side sections so as to permit sliding movement thereof whereby said easel may be adjusted into several operative positions or placed in its inoperative position 70 wherein said easel lies flat against said body.

Signed at New Haven, county of New Haven, State of Connecticut, this 28th day of June, 1929.
